DESIGN FOR A HEARING AID AMPLIFIER

Christian A. Volf, Van Nuys, Calif.

Application June 29, 1940, Serial No. 93,333

Term of patent 7 years

To all whom it may concern:

Be it known that I, Christian A. Volf, a citizen of the United States, residing at Van Nuys, in the county of Los Angeles and State of California, have invented a new, original, and ornamental Design for a Hearing Aid Amplifier, of which the following is a specification, reference being had to the accompanying drawing, forming part thereof.

Figure 1 is a side elevational view of a hearing aid amplifier showing my new design; and

Figure 2 is a top plan view thereof.

I claim:

The ornamental design for a hearing aid amplifier, substantially as shown.

CHRISTIAN A. VOLF.
